(57) **CLAIM**

The ornamental design for a refrigerator shelf, as shown and described.

DESCRIPTION

FIG. 1 is a front view of a refrigerator shelf according to a first embodiment of our design in a first configuration thereof shown in place within an unclaimed refrigerator, a second embodiment of the design in a first configuration being a mirror-image of the first embodiment in the first configuration, and back, right side, left side, top and bottom views of the design showing no claimed portion of the design when in place within the unclaimed refrigerator; FIG. 2 is a front-perspective view of the refrigerator shelf of FIG. 1 with portions of the unclaimed refrigerator removed; FIG. 3 is a top view thereof; FIG. 4 is a bottom view thereof; FIG. 5 is a front elevation view thereof; FIG. 6 is a back elevation view thereof; FIG. 7 is a left side view thereof; FIG. 8 is a right side view thereof;

FIG. 9 is a front perspective view of the refrigerator shelf according to the first embodiment of our design in a second configuration thereof shown in place within an unclaimed refrigerator, the second embodiment of the design in a second configuration being a mirror-image of the first embodiment in the second configuration, and back, right side, left side, top and bottom views of the design showing no claimed portion of the design when in place within the unclaimed refrigerator;

FIG. 10 is a front-perspective view of the refrigerator shelf of FIG. 9 with portions of the unclaimed refrigerator removed;

FIG. 11 is a top view thereof;

(Continued)

FIG. 12 is a bottom view thereof;
 FIG. 13 is a front elevation view thereof;
 FIG. 14 is a back elevation view thereof;
 FIG. 15 is a left side view thereof; and,
 FIG. 16 is a right side view thereof.
 Broken lines are environmental only and form no part of the claimed design.

The diagonal shading indicates transparency.
 The dash-dot depiction of a rectangular prism in FIGS. 2-8, and 9-16 that enclose the refrigerator shelf with portions of the unclaimed refrigerator depicted in FIGS. 1 and 9 removed is similarly unclaimed and represents a space within an interior of the refrigerator in which the shelf may be present.
